(57) **CLAIM**

The ornamental design for an annular flux collector for a valve body, as shown and described.

DESCRIPTION

FIG. 1 is a top view of an annular flux collector for a valve body in accordance with the present design;
FIG. 2 is a bottom view thereof;
FIG. 3 is a back view thereof;
FIG. 4 is a front view thereof;
FIG. 5 is a side view thereof;
FIG. 6 is an opposite side thereof;
FIG. 7 is a perspective view thereof; and,
FIG. 8 is an exploded view thereof.

The broken lines showing portions of the annular flux collector and showing the valve body extension form no part of the claimed design.
